UNITED STATES PATENT OFFICE.

EDWARD I. SNICKERS, OF SHELTON, WASHINGTON.

UMBRELLA AND CANE HOLDER.

1,406,097.

Specification of Letters Patent. Patented Feb. 7, 1922.

Application filed December 29, 1920. Serial No. 433,892.

To all whom it may concern:

Be it known that I, EDWARD I. SNICKERS, a citizen of the United States, residing at Shelton, in the county of Mason and State 5 of Washington, have invented certain new and useful Improvements in Umbrella and Cane Holders, and I do hereby declare the following to be a full, clear, and exact description of the invention, such as will enable others skilled in the art to which it 10 appertains to make and use the same.

This invention relates to new and useful improvements in holders or supports especially adapted for supporting umbrellas and 15 canes and has for its primary object the provision of means, whereby such devices may be held and supported in an upright position and which will permit them to be easily and quickly removed when wanted for use, 20 thereby providing a device especially adaptable for public places to receive umbrellas and canes of visitors, however, the device is extremely useful in private dwellings.

Another object of this invention is the 25 provision of means for catching water that may drip from the umbrellas when supported by the device.

A further object of this invention is the provision of an umbrella and cane support 30 of the above stated character which will be simple, durable and efficient, and which may be manufactured and sold at a comparatively low cost.

With these and other objects in view as 35 will become more apparent as the description proceeds, the invention consists in certain novel features of construction, combination, and arrangement of parts as will be hereinafter more fully described and 40 claimed.

For a complete understanding of my invention, reference is to be had to the following description and accompanying drawings, in which—

45 Figure 1 is a front elevation, illustrating an umbrella and cane support constructed in accordance with my invention.

Figure 2 is a side elevation illustrating the same,

50 Figure 3 is a detail view illustrating a clip,

Figure 4 is a detail sectional view illustrating the water receiving receptacle attached to one of the brackets.

55 Figure 5 is a perspective view illustrating the lowermost bracket.

Referring in detail to the drawings, the numeral 1 indicates supporting rods which are adapted to be attached to a support 2, that may be the wall of a room or any other 60 device which may be conveniently used for such a purpose and said rods are connected to the support 2 by upper and lower brackets 3 and 4. The bracket 3 is secured to the support 2 in any desired manner and has 65 struck out therefrom spaced loops 5 to rotatably receive the supporting rods 1. The lower ends of the supporting rods 1 are journaled in apertures 6 formed in the lower supporting bracket 4. The supporting 70 bracket 4 consists of a horizontal portion 7 and a vertical portion 8 and the latter is secured to the support 2 by suitable fasteners. The lower ends of the supporting rods 1 are journaled in the horizontal portion 7 which 75 is also provided with a series of perforations 9 for the purpose of permitting water dripping from umbrellas supported by said rods to pass through the horizontal portion 7. A conical shaped receptacle 10 is attached to 80 the horizontal portion 7 of the bracket 4 under the perforations for the purpose of receiving or catching the water passing through said horizontal portion from the 85 umbrellas supported by the device.

The upper portions of the supporting rods 1, or the portions that are located above the upper supporting bracket 3 are curved outwardly and upwardly as illustrated at 11 and have their free ends 12 disposed vertically and which are spaced a considerable distance away from the support 2, so that when the handles of umbrellas are attached to said ends 12 by clips 13, said handles of the umbrellas are disposed away from the 95 support 2 so that they may be readily grasped to remove the umbrellas from the holder or support. The clips 13 are substantially U-shaped having their bight portions secured to the ends 12 of the supporting 100 rods 1 while their arms 14 are restricted as illustrated at 15 and curved outwardly so that the handles of umbrellas will be efficiently retained within said clips and the outwardly curved portions of said arms permit 105 the easy insertion of the handles of the umbrellas within the clips.

It is to be noted that this device is also capable of supporting canes or walking sticks as well as umbrellas.

110 While I have shown and described the preferred embodiment of my invention, it

will be understood that minor changes in construction, combination and arrangement of parts may be made without departing from the spirit and scope of the invention as 5 claimed.

Having thus described my invention what I claim is:

An umbrella holder comprising an angular shaped bracket adapted to have its vertical portion secured to a support and having its horizontal portion provided with 10 draining openings and umbrella stick receiving openings of a size larger than the

first openings, means for gripping umbrellas to support them vertically with their sticks inserted in the second mentioned openings, and a receptacle carried by the vertical portion of the bracket and having its open wall underlying the entire horizontal portion of said bracket. 15

In testimony whereof I affix my signature in presence of two witnesses.

EDWARD I. SNICKERS.

Witnesses:

A. N. WARD,
C. E. RUNACRES.
